UNITED STATES PATENT OFFICE

ARTHUR H. WOOD, OF ADRIAN, MICHIGAN, ASSIGNOR TO SIMPLEX PAPER CORPORATION, OF ADRIAN, MICHIGAN, A CORPORATION OF MICHIGAN

BASKET LINER

Application filed October 2, 1929. Serial No. 396,633.

This invention, which relates to liners for baskets wherein is packed fruit, vegetables, or other like commodities, is concerned with certain improvements by which the liner may be produced, shipped and set up with a minimum of expense, be made strong and durable, and be permitted to expand or enlarge, as required to meet conditions without yielding or rupture of the liner material itself. A liner having these characteristics is advantageous in that it is more adaptable to varying conditions, and affords a maximum of protection at all times because of its rugged construction. In the accomplishment of this end I utilize a strip of material, preferably fibrous, bent around to present its two ends in overlapping relation, and provide for such a liner a locking means which, when released, will permit of circumferential movement whereby the liner will enlarge in its entirety. In this manner the liner material itself is not required to yield or rupture, and so may be formed from a wide range of paper stock which is suitable for the intended purpose.

25 An exemplification of my invention is set forth in the accompanying drawings wherein—

Figure 1 is a perspective view of the liner as it appears when set up ready to be filled; 30 Fig. 2 is a side elevation, partly broken away, of a basket in which is fitted the present liner a portion of which is also broken away to exhibit the contents thereof; and

Fig. 3 is a fragmentary detail in elevation showing the releasable means used for connecting the ends of the liner strip.

The present liner A may be made of a paper board or fibrous material having the desired strength and flexibility. Its form is 40 that of a strip having its longer edges preferably curved somewhat so that when the liner is bent into circular form, with its two ends 5 and 6 lapped past each other, the liner will have the general form of a cone frustum. 45 This is desirable, so that the liner will conform better to the inside of an ordinary fruit or vegetable basket B, such as is shown in Fig. 2. For convenience in packing and shipping the liner may be folded transversely as 50 at 7 one or more times. Openings 8 are also

provided through the body of the liner to promote ventilation therethrough.

The two ends of the liner are releasably connected by novel means which will now be explained. As shown, a thread or cord 9 is 55 chain-stitched through the two plies of the liner in the region of its overlapping ends. One end 10 of this thread or cord is extended a sufficient distance to project beyond the upper edge of the liner. At the extremity of 60 this thread or cord may be fastened a tag or check 11 by which to conveniently pull the cord when it is desired to ravel the chain-stitching between the two ends of the liner. As shown in Fig. 1, the chain is normally 65 prevented from raveling by having its extended end 10 pass through the topmost loop, from which it may be readily removed whenever it is desired to separate the two liner ends.

In use, a column of fruit, vegetables, or the like is placed in the liner the ends of which are initially connected by the chain-stitching already described. After the liner, together with its contents, is placed within the basket B, the cord or thread is pulled to break the connection between the two liner ends. When this takes place, the liner is free to enlarge circumferentially in response to pressure of the contents therewithin exerted outwardly 80 against the supporting walls of the basket. It will thus be noted that the chain-stitch connection for the liner ends is required to serve only during the initial stage of packing, the liner being thereafter freed by raveling of the chain-stitch connection to enlarge circumferentially to any extent as permitted by the walls of the basket in which the liner is placed.

I claim:

1. A basket liner for accommodating fruit and the like which consists of a strip of material bendable into circular form with its two ends connected by a cord stitched into a chain extending the length of the ends and diametrically opposed thereon, one end of the cord being extended beyond the proximate end of the liner for manipulation when the stitching is to be raveled.
2. A basket liner for accommodating fruit 100

and the like which consists of a strip of material having its two ends joined by a stitching of chain formation extending substantially the width of the liner and diametrical-
5 ly opposed thereon with one end of the stitching carried past and embracing the proximate edge thereof for convenient manipulation.

3. A basket liner for use in packing fruit and the like, comprising a bendable strip of
10 material with overlapping ends, and a removable continuous means extending the length of and embracing opposite sides of the overlapping ends and being diametrically opposed thereon, said means uniting the ends
15 at short spaced intervals therealong.

4. A basket liner for use in packing fruit and the like, comprising a bendable strip of material with overlapping ends, and a removable continuous flexible member extend-
20 ing the length of and embracing opposite sides thereof, said means diametrically op- posed upon and uniting said ends at short spaced intervals therealong, also securing the upper edges thereof and extending there-
25 beyond to form an overhanging portion adapted to be manipulated to remove the con- tinuous means.

In testimony whereof, I have hereunto set
my hand this 27th day of September, 1929.
